UNITED STATES PATENT OFFICE.

CHARLES EDWARD HAVILAND, OF LIMOGES, FRANCE.

DESIGN FOR A COVERED DISH.

SPECIFICATION forming part of Design No. 25,514, dated May 19, 1896.

Application filed April 15, 1896. Serial No. 587,731. Term of patent 7 years.

To all whom it may concern:

Be it known that I, CHARLES EDWARD HAVILAND, a citizen of the United States, residing at the city of Limoges, in the Republic of France, have invented and produced a new and original Design for a Dish or Tureen, of which the following is a specification, reference being had to the accompanying drawings, forming part thereof, in which—

10 Figure 1 is a side elevation of a dish or tureen bearing and incorporating my design. Fig. 2 is a top view of same, and Fig. 3 is a sectional view of a portion of same on the dotted line 3 3 of Fig. 2.

15 The leading features of my design consist of the ornamental form and configuration of the dish or tureen and its cover, substantially as illustrated in the accompanying drawings.

20 The sides of the dish are composed of the scalloped sections A, which curve inward and downward to the scalloped base B, which bears the ornamentation C. The upper edges of the sides of the dish bear the ornamental

band D, at whose lower edge is the scalloped-scroll ornamentation E. The opposite ends 25 of the dish have the ornamental handles F F.

The cover G has a raised center H, composed of scalloped sections I, having the ornamental outer edging J. At the apex of the raised center H on the cover is the ornamental handle K. The outer edges of the cover G are scalloped to harmonize with the sides of the dish or tureen and bear the lines of ornamentation L M, which harmonize with the ornamental configurations D E on the sides of 35 the dish.

What I claim is—

The design for a dish or tureen and its cover, substantially as shown and described.

Signed at Limoges, in the Republic of 40 France, this 2d day of April, 1896.

CHARLES EDWARD HAVILAND.
